UNITED STATES PATENT OFFICE.

GEORGE BEATTY, WILLIAM G. BEATTY, AND MILTON J. BEATTY, OF FERGUS,
ONTARIO, CANADA.

CARRIER.

No. 854,556.

Specification of Letters Patent.

Patented May 21, 1907.

Application filed November 20, 1905. Serial No. 288,319.

To all whom it may concern.

Be it known that we, GEORGE BEATTY, WILLIAM G. BEATTY, and MILTON J. BEATTY, of Fergus, in the county of Wellington and Province of Ontario, Canada, have invented certain new and useful Improvements in Carriers; and we hereby declare that the following is a full, clear, and exact description of the same.

10 This invention relates to a carrier having a carrier-frame comprising two sides separated by spacing-bars interposed between them below the path of the track and rigidly held in their assembled condition by fastening-bolts and nuts, four track-wheels mounted on axles arranged in two oppositely disposed sets and projecting inwardly from the inner faces of the carrier-frame-sides above the path of the track with an unoccupied space 15 between the track-wheels and axles on one side of the carrier and those on the other side to permit the carrier to freely pass any obstruction on the track, a lever pivoted at one end to one side of the carrier-frame to hold 20 the fixed end of the draw-rope, a rope-guide at the opposite side of the carrier-frame extending below the bottom thereof, a rope-grip pivoted to the last mentioned side of the carrier-frame above and in line with the rope- 25 guide, two guide-pulleys above the rope-grip, journaled on axles connected to the carrier-frame-side with the rope-course between them in line with the rope-course through the rope-grip and rope-guide, a rope-grip-release 30 to position the rope-grip to allow the draw-rope to run freely through the rope-course and to which is pivoted the other end of said lever, a support for the rope-grip-release to maintain it temporarily in an operative position, a carrier-lock forming part of the rope-grip-release and positioned by the latter when actuated to engage two stop members connected to the track so that it will arrest the carrier at the loading point during the 35 hoisting of the load and a cam on the track to engage the rope-grip-release and move it into an operative position when the carrier reaches the loading point, as hereinafter described and particularly pointed out in the appended 40 claims.

For a full understanding of the invention reference is to be had to the following description and to the accompanying drawings, in which,

Figure 1 is a perspective view of the carrier with the rope-grip positioned to allow the draw-rope to move through the rope-course. Fig. 2 is a similar view to Fig. 1, with the rope-grip positioned to grasp the draw-rope and prevent it descending through the rope-course. Fig. 3 is a perspective view of the carrier looking at it from the opposite side to that shown in Fig. 2. Fig. 4 is a longitudinal section of the carrier showing the parts in the same position as in Fig. 1. Fig. 5 is a similar view to Fig. 4 with the parts in the same position as in Fig. 2. Fig. 6 is a detail view of the rope-grip release. Fig. 7 is a view of the inner face of one of the carrier-frame-sides showing part of the slideway for the rope-grip-release. Fig. 8 is a perspective view of the support for the rope-grip-release. Figs. 9 and 10 are perspective views of the rope-grip-release and its slideways showing the parts in the positions shown in Figs. 1 and 2 75 respectively. Fig. 11 is a perspective view of the rope-grip. Fig. 12 is a perspective view of one of the members of the rope-grip. Figs. 13 and 14 are sectional views of the rope-grip with the parts in the same position as shown in Figs. 2 and 1 respectively, and Fig. 15 is a side elevation of the rope-grip-release and lever.

Like letters of reference refer to like parts throughout the specification and drawings. 85

The carrier-frame consists of two sides *a a'* separated by spacing bars *b* located above the bottom of the sides of the carrier-frame but below the path of the track *c* and held assembled by bolts *d d'* and nuts *f f'*. Projecting inwardly from the inner faces of the carrier-frame-sides above the track path are four studs *g* arranged in two oppositely disposed sets with the studs of each set in line, and mounted on the studs *g* are flanged track wheels *h* to move the carrier from one position to another on the track as herein-after described. Pivoted to the lower end of the side *a* at approximately the middle thereof is one end of a lever *a''* from which is suspended a rope-bail *i*, to which is adapted to be attached the fixed end of the draw-rope *j* and attached to the side *a'* is a rope-guide *k* having a rope-course *l* through which the draw-rope passes to the rope-grip pivoted to the carrier-frame side *a'* vertically above the rope-guide *k* and the rope-course there through. The rope-grip consists of two

bifurcated hinge members m m' , the shanks of which are pivoted to the carrier-frame-side a' , by pivot bolts o , and two clasps p , having trunnions q and a clasp p' having trunnions q' mounted in the forks m'' of the hinge members, the centers of the trunnions q being out of line with the centers of the trunnions q' so that they will cause the clasps to separate as the hinge members oscillate upward and cause them to come together as the hinge members oscillate downward.

Mounted on the outer face of the carrier frame side a' , above the rope-grip, are duplex guide pulleys r , r' with the rope-course between them in line with the rope-course through the rope-grip and rope-guide, and protecting the guide-pulleys is a pulley-frame t fastened to the carrier frame side a' , by two sets of bolts u u' fitted with nuts v v' . For convenience of manufacture the bolts u are utilized as the axles for the guide-pulleys, in addition to assisting the bolts u' to fasten the pulley frame to the carrier-frame.

In the inner face of the carrier-frame-side a' , as shown in Figs. 9 and 10, is a vertical slide-way y , in which is movable the rope-grip-release z and to which is hinged the other end of the lever a'' .

Registering in an aperture b' in the lower end of the rope-grip-release is a pin c' which projects from the lower one of the hinge members m' . Extending above the track from the upper end of the rope-grip-release is an arm d'' to be engaged by a cam e' mounted on the track. Pivoted to the lower part of the carrier-frame is a support g' having an arm h' to engage the detent lug i' formed on the side of the rope-grip-release. The cam e' is positioned on the track vertically above the loading point and as the carrier approaches thereto the cam engages the arm d'' as shown in Fig. 5, and raises the rope-grip-release into the position shown in Fig. 4, so that it will actuate the rope-grip to release its grasp on the draw-rope. The support g' then moves by gravity to bring the arm h' into position where it will engage with the detent lug i' and uphold the rope-grip-release, to maintain the rope-grip inoperative while the carrier is at the loading point.

To arrest the carrier at the loading point the under face of the track is provided with two detent stops j' , preferably located below the ends of the cam e' and engaging these stops when the rope-grip-release is actuated is a carrier lock k' forming part of and projecting from the inner face of the rope-grip-release. Co-operating with the carrier is a pulley-block l' , consisting of a pulley frame o' , with a grooved pulley wheel o'' mounted therein and a hook q'' swiveled to the pulley frame. The free end of the hook is bifurcated and pivoted between the forks thereof is a spring tensioned latch r'' which normally

extends across the opening at the mouth of the hook and engages the shank on the opposite side to prevent the withdrawal of the ring of the fork or sling.

The draw-rope j extends from the rope-bail i through the rope-course l in the rope-guide k through the rope course between the clasps p p' of the rope-grip, and between the guide-pulleys r r' , over either of which it extends parallel with the track rail to an idler (not shown). When the carrier is at the loading point the rope-grip-release z is positioned to engage and uphold the rope-grip so that the clasps p p' will be positioned to release the draw-rope and permit it to move freely through the rope-course between them and the carrier lock k' is then positioned to engage the detent stops j' and hold the carrier at the loading point, until the draw-rope has raised the pulley-block into contact with and upset the support g' for the rope-grip-release z . The upsetting of the support g' remove the arm h' from beneath the detent lug i' so that the rope-grip-release can descend to permit the rope-grip to oscillate into a position where it will seize the draw-rope and securely hold it with its suspended load until the rope-grip-release has been actuated by the cam. The strength of the grasp of the rope-grip on the draw-rope is intensified by the weight of the load suspended from the bail which causes the lever a'' to draw upon the rope-grip-release and through the agency of the latter lock the parts of the rope grip against the draw rope and prevent the latter from any ordinary cause moving through them until they have been again released. As the rope-grip-release descends the carrier-lock moves out of the path of the detent stops to allow the carrier to freely move away from the loading point with its load securely suspended.

When the carrier arrives at the delivery point, the load is deposited and the carrier may then be returned to the loading point the approach to which is uninterrupted except by the lifting cam which as soon as the arm d'' comes into contact with it raises the rope-grip-release into its operative position to disengage the grasp of the rope-grip on the draw-rope to allow it to descend for its next load. By providing the carrier-frame with two guide pulleys the direction of the draw-rope may be quickly reversed to draw toward either end of the track. By means of this construction and arrangement of parts the gripping device will grasp the perpendicular part of the draw-rope before it passes over the guide pulleys so that the weight of the load may be utilized to securely lock the rope-grip against the draw-rope.

Having thus fully described our invention what we claim as new and desire to secure by Letters Patent is:

1. A carrier comprising a carrier frame, a

- rope-grip oscillatorily connected thereto, laterally arranged duplex guide pulleys above the rope-grip and having a rope-course alined with the rope-course of the rope-grip, a draw-
5 rope attached at one end to the carrier and extending through the rope-course of the rope-grip and between the guide pulleys to run parallel with the track after passing over either of the guide pulleys, means to automatically move the rope-grip into an inoperative position and holding means for the rope-grip when moved into an inoperative position released by the load.
2. A carrier comprising a carrier-frame, guide-pulleys at one side thereof having a rope-course between them, and a rope grip to seize the draw-rope before passing through the rope-course between the guide-pulleys said rope-grip consisting of a hinge member
10 oscillatorily connected to the carrier-frame and clasp-members mounted in the hinge member having the rope-course between them in line with the rope-course between the guide-pulleys.
- 15 3. A carrier comprising a carrier-frame, guide-pulleys at one side thereof having a rope-course between them, and a rope-grip consisting of a hinge - member oscillatorily connected to the carrier-frame, and oppositely disposed clasp-members having trunnions mounted in the hinge member to cause the clasp-members to respectively grip or release the draw-rope during the oscillation of the hinge-member.
- 20 4. A carrier comprising a carrier-frame, guide-pulleys at one side thereof with a rope-course between them, a rope-grip to seize the draw-rope before passing through the rope-course between the guide-pulleys, and a rope-
25 guide at said side of the carrier-frame having a rope-course in line with that of the rope-grip and guide-pulleys.
5. A carrier comprising a carrier-frame, guide-pulleys at one side thereof with a rope-
30 course between them, a rope-guide at said side of the carrier and below the guide-pulleys, and a rope-grip between the rope-guide and guide-pulleys.
- 35 6. A carrier comprising a carrier-frame, guide-pulleys at one side thereof with a rope-course between them, a rope-guide at said side of the carrier-frame and below the guide-pulleys and a rope-grip between the rope-guide and guide-pulleys consisting of a
40 hinge member pivotally connected to the carrier-frame and clasp-members mounted therein having a rope-course between them in line with the rope-course between the guide-pulleys.
- 45 7. A carrier comprising a carrier-frame, guide-pulleys at one side thereof with a rope-course between them, a rope-grip to seize the draw-rope before passing through the rope-course between the guide-pulleys consisting of hinge-members pivotally connected to the
50 carrier-frame and clasp-members mounted on hinge-members pivotally connected to the carrier-frame and clasp-members having trunnions mounted in the hinge-members to cause the clasp-members to grasp or release the draw-rope as the hinge members oscillate.
- 55 8. A carrier comprising a carrier frame, duplex guide-pulleys at one side thereof and in the same plane as the track with a rope-course between them, a rope-grip having a rope-course alined with that between the
60 guide-pulleys a rope-grip release to render the rope-grip inactive and means for maintaining the rope-grip release in an active position displaced by the load when raised by the draw rope.
- 65 9. A carrier comprising a carrier frame, two duplex guide-pulleys at one side thereof and in the same plane as the track having a rope-course between them, a rope-grip, a rope-grip-release, and a support for the rope-grip release to be tripped by the lifting of the load.
- 70 10. A carrier comprising a carrier-frame, guide-pulleys at one side thereof having a rope-course between them, a rope-grip to seize the draw-rope before passing through the rope-course between the guide-pulleys, a rope-grip-release to render the rope-grip inactive and means for maintaining the rope-grip-release in an active position displaced by the load when raised by the draw-rope in combination with the track, and a cam thereon to actuate the rope-grip-release.
- 75 11. A carrier comprising a carrier-frame, guide-pulleys at one side thereof having a rope course between them, a rope-grip to seize the draw-rope before passing through the rope-course between the guide-pulleys, a rope-grip-release and a support for the rope-grip-release pivoted to the carrier frame to be tripped by the lifting of the load, in combination with the track and a cam thereon to actuate the rope-grip-release.
- 80 12. A carrier comprising a carrier-frame, guide-pulleys at one side thereof having a rope-course between them, a rope-grip to seize the draw-rope before passing through the rope-course between the guide-pulleys, a rope-grip-release to actuate the rope-grip, a carrier lock for the rope-grip-release and means for maintaining the rope-grip-release in an active position and a support for the rope-grip-release displaced by the load when raised by the draw-rope, in combination with the track, a cam thereon to actuate the rope-grip-release and detent stops for the track to be engaged by the carrier-lock.
- 85 13. A carrier comprising a carrier-frame, duplex guide-pulleys at one side thereof and in the same plane as the track with a rope-course between them, a rope-grip, a rope-grip-release, means for maintaining the rope-grip-release in an active position displaced by the load when raised by the draw-rope, track wheels mounted on axles on the inner faces of

carrier-frame and oppositely disposed clasp-members having trunnions mounted in the hinge-members to cause the clasp-members to grasp or release the draw-rope as the hinge members oscillate.

70

8. A carrier comprising a carrier frame, duplex guide-pulleys at one side thereof and in the same plane as the track with a rope-course between them, a rope-grip having a rope-course alined with that between the guide-pulleys a rope-grip release to render the rope-grip inactive and means for maintaining the rope-grip release in an active position displaced by the load when raised by the draw rope.

75

9. A carrier comprising a carrier frame, two duplex guide-pulleys at one side thereof and in the same plane as the track having a rope-course between them, a rope-grip, a rope-grip-release, and a support for the rope-grip release to be tripped by the lifting of the load.

80

10. A carrier comprising a carrier-frame, guide-pulleys at one side thereof having a rope-course between them, a rope-grip to seize the draw-rope before passing through the rope-course between the guide-pulleys, a rope-grip-release to render the rope-grip inactive and means for maintaining the rope-grip-release in an active position displaced by the load when raised by the draw-rope in combination with the track, and a cam thereon to actuate the rope-grip-release.

85

11. A carrier comprising a carrier-frame, guide-pulleys at one side thereof having a rope course between them, a rope-grip to seize the draw-rope before passing through the rope-course between the guide-pulleys, a rope-grip-release and a support for the rope-grip-release pivoted to the carrier frame to be tripped by the lifting of the load, in combination with the track and a cam thereon to actuate the rope-grip-release.

95

12. A carrier comprising a carrier-frame, guide-pulleys at one side thereof having a rope-course between them, a rope-grip to seize the draw-rope before passing through the rope-course between the guide-pulleys, a rope-grip-release to actuate the rope-grip, a carrier lock for the rope-grip-release and means for maintaining the rope-grip-release in an active position and a support for the rope-grip-release displaced by the load when raised by the draw-rope, in combination with the track, a cam thereon to actuate the rope-grip-release and detent stops for the track to be engaged by the carrier-lock.

100

105

110

115

120

125

130

13. A carrier comprising a carrier-frame, duplex guide-pulleys at one side thereof and in the same plane as the track with a rope-course between them, a rope-grip, a rope-grip-release, means for maintaining the rope-grip-release in an active position displaced by the load when raised by the draw-rope, track wheels mounted on axles on the inner faces of

the carrier-frame-sides having unoccupied spaces between them for the track and the parts mounted thereon.

14. A carrier comprising a carrier-frame, 5 guide-pulleys at one side thereof with a rope-course between them, a rope-grip to seize the draw-rope before passing through the rope-course between the guide-pulleys, track-wheels mounted on the inner faces of the carrier-frame-sides having unoccupied spaces between them for the parts mounted on the track, a rope-grip-release and a carrier-lock forming part thereof and means for maintaining the rope-grip-release in an active position 10 displaced by the load when raised by the draw-rope, in combination with the track, a cam mounted thereon to actuate the rope-grip-release and detent stops to be engaged by the carrier lock.
15. A carrier comprising a carrier-frame, 15 guide-pulleys at one side thereof with a rope-course between them, a rope-grip, a rope-grip-release to actuate the rope-grip and a lever connected to the rope-grip-release and to one side of the carrier-frame.
16. A carrier comprising a carrier frame, 20 guide-pulleys at one side thereof with a rope-course between them, a rope-grip, a rope-grip-release, a support for the rope-grip-release arranged to be tripped by the lifting of the load and a lever connected to the rope-grip-release and to one side of the carrier-frame.
17. A carrier comprising a carrier-frame, 25 guide-pulleys at one side thereof with a rope-course between them, a rope-grip to seize the draw-rope before passing through the rope-course between the guide-pulleys, and a rope-grip-release to actuate the rope-grip, in combination with the track, a cam thereon to actuate the rope-grip-release and a lever connected to the rope-grip-release and to one side of the carrier-frame.
18. A carrier comprising a carrier-frame, 30 guide-pulleys at one side thereof with a rope-course between them, a rope-grip to seize the draw-rope before passing through the rope-course between the guide-pulleys, a rope-grip-release and a support for the rope-grip-release pivoted to the carrier-frame and arranged to be tripped by the lifting of the load, in combination with the track, a cam thereon to actuate the rope-grip-release, and a lever connected to the rope-grip-release and to one side of the carrier-frame.
19. A carrier comprising a carrier-frame,

guide-pulleys at one side thereof with a rope-course between them, a rope-grip to seize the draw-rope before passing through the rope-course between the guide-pulleys, a rope-grip-release to actuate the rope-grip and a carrier-lock for the rope-grip-release, in combination with the track, a cam thereon to actuate the rope-grip-release, detent stops for the track to be engaged by the carrier lock and a lever connected to the rope-grip-release and to one side of the carrier-frame.

20. A carrier comprising a carrier-frame, 6c guide-pulleys at one side thereof with a rope-course between them, a rope-grip to seize the draw-rope before passing through the rope-course between the guide-pulleys, a rope grip release, track-wheels mounted on axles on the inner faces of the carrier-frame-sides having unoccupied spaces between them for the 70 track and the parts mounted thereon and a lever connected to the rope-grip-release and to one side of the carrier-frame.

21. A carrier comprising a carrier-frame, 75 guide pulleys at one side thereof with a rope-course between them, a rope grip, a rope-grip-release and track-wheels mounted on axles on the inner faces of the carrier-frame-sides having unoccupied spaces between them for the 80 track and the parts mounted thereon in combination with the track, a cam mounted thereon to actuate the rope-grip-release and a lever connected to the rope-grip-release and to one side of the carrier frame.

22. A carrier comprising a carrier-frame, 85 guide-pulleys at one side thereof with a rope-course between them, a rope-grip to seize the draw-rope before passing through the rope-course between the guide-pulleys, track-wheels mounted on the inner faces of the carrier-frame-sides having unoccupied spaces 90 between them for the parts mounted on the track, a rope-grip-release, a carrier lock forming part thereof and a lever connected to the rope-grip release and to one side of the carrier frame, in combination with the track and a cam mounted thereon to actuate the rope-grip-release, and detent stops to be engaged by the carrier-lock.
